CLAIM

We claim the ornamental design for underwear jeans, as shown and described.

DESCRIPTION

FIG. 1 is a front view of underwear jeans showing our new design;

FIG. 2 is another front view, showing the upper portion of the jeans in an opened condition, thereof;

FIG. 3 is a rear view thereof; and,

FIG. 4 is a side view thereof.

The broken lines on the surface of the jeans in FIGS. 1-4 represent stitching.
